(57) **CLAIM**

The ornamental design for blender attachment, as shown and described.

DESCRIPTION

FIG. 1 is a perspective view of a blender attachment, showing our new design in a first embodiment;

FIG. 2 is a front view of the embodiment shown in FIG. 1; FIG. 3 is a back view of the embodiment shown in FIG. 1; FIG. 4 is side view of the embodiment shown in FIG. 1; FIG. 5 is another side view of the embodiment shown in FIG. 1;

FIG. 6 is a top view of the embodiment shown in FIG. 1; FIG. 7 is a bottom view of the embodiment shown in FIG. 1;

FIG. 8 is another perspective view of the embodiment shown in FIG. 1, as shown in a blender environment;

FIG. 9 is a perspective view of a blender attachment, showing our new design in another embodiment;

FIG. 10 is a front view of the embodiment shown in FIG. 9; FIG. 11 is a back view of the embodiment shown in FIG. 9; FIG. 12 is side view of the embodiment shown in FIG. 9; FIG. 13 is another side view of the embodiment shown in FIG. 9;

FIG. 14 is a top view of the embodiment shown in FIG. 9; FIG. 15 is a bottom view of the embodiment shown in FIG. 9;

FIG. 16 is another perspective view of the embodiment shown in FIG. 9, as shown in a blender environment;

FIG. 17 is a perspective view of a Blender Attachment, showing new design in another embodiment;

FIG. 18 is a front view of the embodiment shown in FIG. 17;

FIG. 19 is a back view of the embodiment shown in FIG. 17;

FIG. 20 is side view of the embodiment shown in FIG. 17; FIG. 21 is another side view of the embodiment shown in FIG. 17;

FIG. 22 is a top view of the embodiment shown in FIG. 17; FIG. 23 is a bottom view of the embodiment shown in FIG. 17;

(Continued)

FIG. 24 is another perspective view of the embodiment shown in FIG. 17, as shown in a blender environment
 FIG. 25 is a perspective view of a blender attachment, showing our new design in another embodiment;
 FIG. 26 is a front view of the embodiment shown in FIG. 25;
 FIG. 27 is a back view of the embodiment shown in FIG. 25;
 FIG. 28 is side view of the embodiment shown in FIG. 25;
 FIG. 29 is another side view of the embodiment shown in FIG. 25;
 FIG. 30 is a top view of the embodiment shown in FIG. 25;
 FIG. 31 is a bottom view of the embodiment shown in FIG. 25;
 FIG. 32 is another perspective view of the embodiment shown in FIG. 25, as shown in a blender environment;
 FIG. 33 is a perspective view of a blender attachment, showing our new design in another embodiment;
 FIG. 34 is a front view of the embodiment shown in FIG. 33;
 FIG. 35 is a back view of the embodiment shown in FIG. 33;
 FIG. 36 is side view of the embodiment shown in FIG. 33;
 FIG. 37 is another side view of the embodiment shown in FIG. 33;
 FIG. 38 is a top view of the embodiment shown in FIG. 33;
 FIG. 39 is a bottom view of the embodiment shown in FIG. 33; and,
 FIG. 40 is another perspective view of the embodiment shown in FIG. 33, as shown in a blender environment.
 The broken lines in the figures are for environmental purposes only and form no part of the claimed design.
 The stippling shown in the embodiments of FIGS. 25-32 represents a contrast in appearance and/or material from the other claimed portions of the design in the embodiments of FIGS. 25-32.
 The stippling shown in the embodiments of FIGS. 33-40 (which is a lighter relative to the stippling in the embodiments of FIGS. 25-32) represents a brushed metallic surface such as stainless steel.
